UNITED STATES PATENT OFFICE.

NICHOLAS L. HEINZ, OF LA SALLE, ILLINOIS.

NITER-DECOMPOSING APPARATUS.

1,315,834.

Specification of Letters Patent. Patented Sept. 9, 1919.

Application filed September 15, 1915. Serial No. 50,910.

To all whom it may concern:

Be it known that I, NICHOLAS L. HEINZ, a citizen of the United States, residing at La Salle, in the county of La Salle and State 5 of Illinois, have invented a new and useful Niter-Decomposing Apparatus, of which the following is a specification.

My invention relates to apparatus for decomposing niter, and the objects of my invention are, first, to provide means for decomposing the sodium nitrate in a sulfuric acid system irrespective of the working of the balance of the system; second, to enable independent control of the decomposing 15 action of the sodium nitrate; third, to afford a system of decomposing niter of greater efficiency than has heretofore been attained; and other objects to become apparent from the description to follow.

20 Heretofore in sulfuric acid systems the necessary nitrogen compounds have been introduced between the sulfur burners and the Glover tower by placing in the flue leading from the burners to the tower, one or more 25 cast iron boxes containing sodium nitrate and sulfuric acid, depending on the heat passing from the burners to decompose the sodium nitrate and liberate the nitrogen compounds. By said system the liberation 30 of the nitrogen compounds cannot be controlled except by controlling the heat at the burners, which is very unsatisfactory and at times results in the boiling over of the sodium nitrate and thus filling the flue. 35 Furthermore it is very desirable to be able at all times to control the liberation of the nitrogen compounds. By the use of my invention the heat admitted to the cast iron boxes containing sodium nitrate is under 40 absolute control of the operator so that when the process is for any reason interrupted the liberation of the nitrogen compounds can be controlled accordingly.

To describe my invention so that others 45 versed in the art to which it pertains can make and use the same I have illustrated it on the accompanying drawing forming a part of this specification, in which:—

Figure 1, is a longitudinal sectional view 50 of a portion of a flue leading from the sulfur burners to the Glover tower, showing an embodiment of my invention, and Fig. 2, is a sectional view taken on line 2—2 of Fig. 1, looking in the direction indicated by 55 the arrows.

Similar reference characters refer to similar parts throughout both views.

The flue 3 leads from the sulfur burners, not shown, to the Glover tower, not shown, and for a portion of its course it is preferably extended at a lower level as indicated at 4 having the downward bend 5 and the upward bend 6. The cast iron boxes 7 are placed just below the part 4 of flue 3 with their upper discharge openings communicating with the flue so that the nitrogen compounds liberated from the sodium nitrate placed in the boxes 7 will enter the part 4 of flue 3 and mix with the sulfurous gases coming from the burners. The bends 5 and 6 in the flue 3 serve to give a whirling motion to the gases passing therethrough and serve to thoroughly mix the sulfurous gases and the nitrogen compounds liberated from the boxes 7.

Below each box 7 is arranged a fire box 8 having a grate 9 and a suitable smoke flue 10. The fire under each box 7 is regulated to retain the contents of the box at the desired temperature to attain the best 75 results. Suitable shut off dampers 11 are provided above the boxes 7 to shut off communication with flue 3 whenever necessary, as for instance when a new box has to be substituted for a broken one. Thus it is 80 clear that the supply of nitrogen compounds 85 can be perfectly controlled even during interruptions due to breakdowns, changes in temperature, atmospheric changes, etc.

Each box 7 is provided with a discharge 90 snout 12 at its bottom through which the remaining niter cake is discharged into a cake mold 13 after the nitrogen compounds have been sufficiently liberated. The exit of the snout 12 is normally closed by a suitable 95 cap 14.

It will be understood that the size, shape and arrangement of the parts may be varied without in the least departing from the scope of my invention.

Having thus fully described my invention what I claim as new and desire to secure by Letters Patent is:—

1. In a niter decomposing apparatus, a flue, a sodium nitrate receptacle having its upper 105 open part in communication with said flue, an independent furnace for heating said receptacle, whose hot gas flue is prevented from communicating with said first named flue by the interpositioning of said recep- 110

- tacle and a damper arranged immediately above said receptacle to prevent communication between the two flues when the receptacle is removed.
5. 2. In a niter decomposing apparatus, a flue, a sodium nitrate receptacle provided with a discharge opening in its bottom and having its upper open part in communication with said flue, an independent furnace 10 for heating said receptacle whose hot gas flue would communicate with said first named flue if said receptacle were removed and means between said two flues for preventing communication between the said two 15 flues when the receptacle is removed.
3. In a niter decomposing apparatus, a flue, a fire box comprising a flue connecting with said first named flue, a sodium nitrate receptacle in the last named flue and normally 20 shutting off communication between said two flues and a damper to shut off the communication between said two flues so
- that the said receptacle can be removed without opening communication between said two flues.
4. In a niter decomposing apparatus, a horizontally disposed flue, a fire box comprising a vertically disposed flue connecting with said horizontally disposed flue, a sodium nitrate receptacle in the upper part 30 of said last named flue and normally shutting off communication between the said two flues and a damper to shut off the communication between said two flues so that the said receptacle can be removed without 35 opening communication between said two flues.

In testimony whereof I have signed my name to this specification in presence of a subscribing witness this 9th day of August, 40 1915, at Pittsburgh, Pennsylvania.

NICHOLAS L. HEINZ.
